UNITED STATES PATENT OFFICE.

LYMAN O. GOODWIN, OF NORTH ANDOVER, MASSACHUSETTS, ASSIGNOR TO DAVIS & FURBER MACHINE COMPANY, OF NORTH ANDOVER, MASSACHUSETTS, A CORPORATION OF MASSACHUSETTS.

REVOLUTION-INDICATING MECHANISM FOR SPINNING-MACHINES.

No. 879,957.

Specification of Letters Patent.

Patented Feb. 25, 1908.

Application filed October 22, 1903. Serial No. 178,066.

To all whom it may concern:

Be it known that I, LYMAN O. GOODWIN, a citizen of the United States, residing at North Andover, in the county of Essex and State of Massachusetts, have invented an Improvement in Revolution-Indicating Mechanism for Spinning-Machines, of which the following description, in connection with the accompanying drawings, is a specification, like letters on the drawings representing like parts.

Spinning machines, a variety of which is instanced in the mule, employ what is known in the textile art as time-wheel mechanism, said mechanism being provided for determining usually a certain number of rotations of parts of the machine, or periods during which certain parts may operate with relation to other parts of the machine.

I have herein shown my invention as cooperating with a worm deriving its motion from the main or driving shaft of the mule, such for instance as represented in United States Patent No. 272,401, February 20, 1883, and to indicate the amount of twist being put into the yarn. The devices herein shown are, however, applicable to roving, drawing and other rollers or shafts employed in spinning machines of which the mule is a type.

Prior to my invention in all the time-wheel or revolution indicating mechanism so far as I am aware, the worm-toothed wheel of such mechanism is carried by a sliding-frame and is intermittently engaged with a worm on a drive shaft, but herein I have mounted said wheel on a stud stationary with the frame, and have provided for the constant engagement of the worm-toothed wheel with its actuating worm, and said wheel which is moved constantly during the operation of the machine constitutes driving means for the indicator or time-wheel, the latter term being the technical designation thereof.

Figure 1 in elevation looking at the end of the mule behind the head shows a sufficient portion of a mule with my improvements added, some parts of which are shown in section, to enable the same to be understood; Fig. 1^a a detail showing part of the edge of the indicator wheel with the dog held thereon as in Fig. 1; Fig. 2 is a right hand view of the parts shown in Fig. 1, with the exception

that the stand and lever forming part of the clutch closing means are omitted and the dog 22 removed; Fig. 3 shows in side elevation and end view the clutch sleeve removed from the indicator wheel; Fig. 4 shows detached the upper part of the lever; Fig. 5 shows an edge and face view of the hub of the worm-toothed wheel C²; Fig. 6 in two views shows the dog 22 detached, and Fig. 7 shows the lever 24, 25 detached.

Referring to the drawings, A represents part of the head of a mule to which is bolted by suitable bolts A¹ a guideway A' grooved at one side to receive and guide a sliding-frame A² provided with a cam A⁴ constituting the moving device for the clutch-closing means to be described. This sliding-frame is fitted to be moved vertically in the guideway A' by the usual gear having a cam-roll and deriving its motion from the drawing-in shaft as in said patent, has a projection A⁵ that constitutes a hand-piece by which to lift the sliding-frame when desired. The sliding-frame also sustains a bolt A⁶ on which is pivoted a locking-device A⁷ made as a hook that when engaged with a projection A⁸ extended from a bracket A⁹ secured to the guideway A', by bolts A¹⁰, as in Fig. 1, or it may be to the head of the mule, locks the sliding-frame in its operative position.

The locking-device or hook A⁷ at its upper end has a pin a⁷, and a spring a⁸ surrounds a bolt a⁹ fixed to the cam A⁴ extended loosely through a hole in a lug a¹⁰ on the hook A⁷ the spring acting normally to cause said locking-device, whenever the sliding-frame is lifted in usual manner during the operation of the mule, to engage the projection A⁸. The head has a depending bracket C which acts with the guideway to sustain the opposite ends of a stud C' shaped as best shown by full lines Fig. 1, said stud being held fixedly in position by nuts b, b', applied thereto at its opposite ends. The stud has a shoulder 5 which abuts against a boss 8 of the guideway, and said stud also has another shoulder against which is received a washer 9 that loosely surrounds the stud and furnishes a seat for one end of a cushioning spring 10 which also surrounds the stud and is received between said washer and the boss 8.

The stud has applied to it loosely next said washer a worm-toothed wheel C² that consti-

tutes a constantly moving actuator for an indicator-wheel C^3 to be described, the latter also having the stud C' as its center of motion. The right-hand end of the hub of the worm-wheel C^2 has a series of clutch-teeth 12, see Figs. 1 and 5.

The hub of the indicator-wheel C^3 at its right hand side has an extension shown as provided with a flange 13 with which is connected a rope 14 to which is attached in practice a weight, not shown, which serves to revolve the indicator-wheel backwardly into its starting position after each complete operation thereof, and after the descent of the sliding-frame, which takes place once during each cycle of operations of the member or part of the spinning machine or mule with which said indicator-wheel is arranged to co-operate, and as herein illustrated it is understood that the indicator-wheel is moved during the time that the twist is being put into the yarn, and is stopped after the predetermined amount of twist has been reached.

Surrounding the stud C' is a collar 7 which abuts a shoulder formed in the right-hand side of the hub of the worm-wheel C^2 , as best seen in Fig. 1, and resting against said collar is one end of a spiral spring 15, the outer or right-hand end of which abuts a washer 16 located within a chamber of a clutch member or sleeve C^4 , see Fig. 1, said clutch having teeth 12^x that co-act with the clutch-teeth 12 of the wheel C^2 , said toothed parts constituting the clutch for coupling the indicator-wheel to the worm-toothed wheel whenever it is desired that the continuously moving actuator shall pick up and rotate the indicator-wheel for substantially a full rotation or less, that the indicator-wheel may act and fulfil the purpose required of it. The spiral spring 15 whenever free to act so moves the clutch part referred to as to permit the wheel C^2 to continue its rotation and not affect the indicator-wheel. Part of the sleeve C^4 carrying the clutch-teeth is extended as shown at 17, nearly to the outer end of the hub of the indicator-wheel, which latter abuts a stop 18 at the inside of the bracket C.

The lower end of the bracket C has an opening in which is located a bolt 19 on the extremities of which is pivoted a forked lever C^6 having an adjustable arm C^7 . The forked end of the lever contacts with the outer end of the clutch sleeve C^4 , and the arm C^7 is acted upon by the cam A^4 before described carried by the sliding-frame, whenever said frame is lifted in the usual manner by or through the roller-carrying gear driven by the drawing-in shaft, causing said lever to move the clutch sleeve C^4 to the left preparatory to clutching the indicator-wheel operatively with the continuously moving actuator C^2 .

The lever and cam constitute one form of what I shall hereinafter designate "clutch actuating means," they being represented in

position to effect the clutching of the indicator-wheel with and to be rotated by the wheel C^2 . The adjustment of the arm C^7 of the lever C^6 enables the lever to be lengthened so that through the inclined edge of the cam A^4 the forked end of the lever may be made to contact just as required with the outer end 17 of the clutch sleeve C^4 .

The indicator-wheel has extended entirely about its edge a series of holes 20 in any one of which may be entered a pin 21, carried by a dog 22, having a backward projection 220, said dog embracing the edge of the indicator-wheel, and the pin connecting the dog with any hole of the indicator-wheel. The adjustment of the dog on the indicator-wheel by placing the pin 21 in any preferred hole 20 provides for variations in the extent of the twist to be put into the yarn, or provides for any desired "number of holes of twist," or provides for the rotation of the indicator-wheel for a definite period before the indicator-wheel will be disconnected from its driving means.

The indicator-wheel has upon its face an index line for each hole 20, and as shown there are seventy-five lines divided in groups of five, and the groups are numbered from zero to 75. By numbering the face of the wheel as illustrated instead of marking the wheel with a number next each hole 20, it is possible to more readily read the number on the wheel by looking at the pin, the latter lining with one or the other of the marks, instead of looking for the number next the hole, some of which numbers at times will be covered by the dog 22.

Heretofore in this class of apparatus the pin has been carried by a worm-wheel, and it has been customary to determine by actual count the number of the hole in the worm-wheel in which the pin was to be placed to provide for turning the worm-wheel for the desired length of time before the worm-wheel was disconnected from its driving means. In this my invention by reason of the index lines or figures on the face of the wheel, one may see at once without the necessity of counting, in which one is frequently liable to make a mistake, in which of the series of holes 20 to insert the pin 21, and hold the dog, to secure the rotation of the wheel for the desired period, or until the desired number of holes of twist have been gained.

The face of the indicator-wheel has a pin 23 that when the indicator-wheel is to be started occupies a position at the right, see Fig. 2, of and contacts with an arm 24 depending from a collar 25, loosely surrounding the inner end of the clutch sleeve C^4 , the lower end of said arm at such time being represented as interposed between the projection A^8 and the pin a^7 of the locking-device A^7 ; said pin 23 by contact with said arm, as the rope and weight described act to turn the indicator-wheel in a

direction opposite the arrow, Fig. 2, arrests the indicator-wheel in its normal or starting position.

Now, as the indicator-wheel surrounding the clutch sleeve C^4 and operatively engaged with the wheel C^2 is rotated in the direction of the arrow, Fig. 2, the projection 220 of the dog 22 finally meets the left-hand side of the arm 24 and turns said arm to the right from the position Fig. 2, causing the extremity of said arm in contact with pin a^7 to turn the locking-device aside from its engagement with the projection A^8 , and thereafter a spring d , partially shown and connected at one end with said sliding-frame and at its lower end to some fixed spot, depresses the sliding-frame and its cam A^4 , the latter retiring from its contact with the lower end C^7 of the lever C^6 . As soon as this happens the spring 15 immediately expands and moves the clutch sleeve C^4 to the right, disengaging its teeth from the clutch teeth 12 of the worm-toothed wheel C^2 and turning the lever C^6 on its fulcrum until said lever meets a stop d^2 . When the sliding-frame is again lifted in usual manner, as before stated, by or through the drawing-in shaft, the cam A^4 meets the lower end of the lever C^6 and turns said lever to thereby move to the left, viewing Fig. 1, the clutch sleeve C^4 , causing it to engage the clutch teeth 12 of the worm-toothed wheel, and thereafter said wheel immediately takes up and rotates in unison with it the indicator-wheel, turning the latter until the projection 220 again through the arm 24 disengages the locking-device and permits the descent of the sliding-frame. Herein it will be understood that the teeth of the worm-toothed wheel C^2 are always in mesh with the constantly moving driving device represented as the usual worm 3 fast on a shaft D^4 having a bevel pinion D^5 that is engaged by a bevel pinion D^6 on the main driving or power shaft D^7 of the machine.

It will be understood that different parts of a spinning machine and especially of a mule have to be turned for a definite number of revolutions, such for instance as the roving rollers, and drawing-rollers, and revolution indicating-wheel mechanism substantially such as herein described is applicable not only to determine the extent of twist, but also the number of rotations of said rollers.

Heretofore, as stated, the worm-toothed wheel has been driven intermittently by a worm, but such wheel has never so far as I am aware been driven continuously, as herein provided for, and consequently the usual trouble arising from the improper contact of the teeth of the worm-wheel with the worm is obviated; and so also it is unnecessary to provide a tooth or device which may yield as the worm-teeth go into mesh with the teeth of the worm to thereby prevent damage of parts in case of fault in mesh.

I believe that I am the first in machines of the class described to drive an indicator-wheel intermittently from a worm gear that is moved substantially continuously during the operation of the machine; and also the first to drive an indicator-wheel through a clutch from a continuously rotating actuator, and I desire to claim these features broadly, as the parts shown in carrying out my invention in one of the best forms now known to me, might be changed in shape and be variously modified and yet include the gist of my invention, which is defined in the claims hereinafter presented.

I also believe that I am the first to provide an indicator-wheel having a series of holes, either of which may receive the twist pin, with graduations to indicate instantly to the eye the number of holes of twist.

Having described my invention, what I claim and desire to secure by Letters Patent is:

1. In mechanism of the class described, an indicator-wheel, a continuously moving actuator, a clutch to operatively connect said indicator-wheel and actuator, means to hold the clutch positively in engagement, means tending normally to disengage the clutch, and separate means to automatically release the clutch from control of said holding means, to free the indicator-wheel from the actuator.

2. In mechanism of the class described, an indicator-wheel, a continuously moving actuator, a clutch intermediate said parts, means tending normally to disengage the clutch, positively acting means to hold the clutch in engagement, and automatically operating means to move the means to hold the clutch when the indicator-wheel is to be moved by said actuator.

3. In mechanism of the class described, a continuously moving actuator, having a clutch part rotated thereby, an indicator-wheel, a second clutch part rotatable therewith, automatic means to engage said clutch parts when the indicator-wheel is to be turned by the actuator, means to lock the clutch parts in engagement, and means actuated by the indicator-wheel to unlock the locking means and to permit disengagement of the clutch parts.

4. In mechanism of the class described, a worm-toothed gear, a continuously moving member always in mesh therewith, and moving the same continuously, an indicator-wheel, a clutch intermediate the indicator-wheel and the gear to operatively connect them, and clutch disengaging means controlled by the indicator-wheel.

5. In mechanism of the class described, a worm shaft having a worm, a non-rotatable stud fixed with relation to the worm-shaft, a worm-toothed gear rotatably mounted on the stud and in mesh continuously with the worm, an indicator-wheel, and means to

- couple the same operatively with said worm-toothed gear, that the latter may rotate the indicator-wheel for a predetermined part of a revolution.
5. 6. In mechanism of the class described, an indicator-wheel, a continuously-moving actuator therefor, a clutch intermediate the indicator-wheel and actuator, and manually adjustable, automatic means actuated by 10 the indicator-wheel to control the release of the clutch, to thereby free the indicator-wheel from the actuator.
7. In mechanism of the class described, an indicator-wheel, a continuously-moving actuator, a clutch intermediate and to operatively connect said indicator-wheel and actuator, means to throw the clutch into engagement, and adjustable means actuated by the indicator-wheel to automatically 20 effect disengagement of the clutch at a predetermined point in the rotation of the indicator-wheel.
8. In mechanism of the class described, an indicator-wheel, a continuously moving actuator therefor, a clutch intermediate said indicator-wheel and actuator, and a member 25 adjustably mounted on the indicator-wheel and adapted to cause the release of the clutch.
9. In mechanism of the class described, an indicator-wheel, a continuously moving actuator, a clutch intermediate said indicator-wheel and actuator, a lock to hold the clutch in engagement, and means actuated by the indicator-wheel to release the lock. 30
10. In mechanism of the class described, an indicator-wheel, a continuously-moving actuator, a clutch for driving the indicator-wheel from the actuator, a locking device to hold the clutch in engagement, means actuated by the indicator-wheel to release the locking device, and automatically operated means to release the clutch when the locking device is released. 35
11. In mechanism of the class described, a continuously moving actuator, an indicator-wheel, a clutch intermediate said indicator-wheel and actuator, means to hold the clutch in engagement, and clutch-disengaging means controlled by the indicator-wheel. 40

In testimony whereof, I have signed my name to this specification, in the presence of two subscribing witnesses.

LYMAN O. GOODWIN.
